UNITED STATES PATENT OFFICE.

JOHN A. PLUEBELL, OF NORTH BRADDOCK, AND JOHN E. KAUTZ, OF RANKIN,
PENNSYLVANIA.

RAIL-FASTENER.

1,060,285.

Specification of Letters Patent.

Patented Apr. 29, 1913.

Application filed November 6, 1912. Serial No. 729,896.

To all whom it may concern:

Be it known that we, (1) JOHN A. PLUEBELL and (2) JOHN E. KAUTZ, citizens of the United States of America, residing at (1) 5 North Braddock and (2) Rankin, in the county of Allegheny and State of Pennsylvania, have invented certain new and useful Improvements in Rail-Fasteners, of which the following is a specification, reference being had therein to the accompanying drawing.

This invention relates to a rail fastener, and the objects of our invention are to provide a fastener that can be advantageously used for connecting the abutting or confronting ends of rails without resorting to the use of bolts or nuts, and to provide interlocking splice bars that firmly brace the sides of rails and prevent vertical and lateral displacement of the same.

Further objects of our invention are to provide a rail fastener embodying splice bars that support rails whereby rolling stock will have practically a continuous support 15 or tread thereby eliminating jarring and bumping and the breaking down of wheels, and to accomplish the above results by a mechanical construction that is durable, easy to install, inexpensive to manufacture, and 20 highly efficient for use in connection with various types of rails.

With the above and other objects in view the invention resides in the novel construction, combination and arrangements of parts 25 to be hereinafter specifically described and then claimed.

Reference will now be had to the drawing, wherein:—

Figure 1 is an elevation of one side of a 40 rail fastener in accordance with our invention, Fig. 2 is a longitudinal sectional view of the same, Fig. 3 is an end view of the rail fastener, Fig. 4 is a cross sectional view of the same, Fig. 5 is an elevation of the opposite side of the fastener from that shown in Fig. 1, and Fig. 6 is a plan of the rail fastener.

A rail fastener in accordance with our invention comprises splice bars 1 having interlocking base plates 2 and 3 adapted to support the base flanges 4 of rails 5 that are braced by said splice bars. The base plate 2 has a plurality of tongues 6 extending into openings 7 provided therefor in one splice bar, and the base plate 3 has tongues 8 ex-

tending into openings 9 provided therefor in the other splice bar. The tongues 6 of the base plate 2 are alternately arranged relatively to the tongues 8 of the base plate 3 and these tongues prevent longitudinal displacement of one splice bar relatively to the other.

The splice bars 1, intermediate the ends thereof, are provided with enlargements 10 and depending curved arms 11, said arms 65 contacting at a point directly beneath the base plates 2 and 3, as shown in Figs. 3 and 4. The splice bars 1 and the enlargements and arms thereof are provided with vertically alining openings 12 and registering 70 with these openings are openings 13 in the tongues 6 and 8 of the base plates 2 and 3. Extending through these openings are tapering spike-shaped keys 14 having the upper ends thereof provided with heads 15 75 and the lower ends with openings 16. Extending through the openings 16 are cotter pins 17 employed for locking the keys 14 in position. Ordinary spikes 18 pass through the outermost openings 12 and 13 80 for securing the rail fasteners to ties, sleepers or other supports 20. Coöoperating with the spikes 18 are spikes 19 engaging the edges of one of the splice bars and extending into the ties 20.

It is thought that the utility of a rail fastener in accordance with this invention will be apparent without further description, and while in the drawing there is illustrated a preferred embodiment of the invention, it is to be understood that the structural elements are susceptible of such changes, as in the size, shape and manner of assemblage as fall within the scope of the appended claims.

What we claim is:—

1. In a rail fastener, the combination with rails, of splice bars bracing the sides of said rails, interlocking base plates carried by said splice bars and supporting said rails, 100 tongues carried by one of said base plates and extending into openings in one of said splice bars, tongues carried by the other base plate and extending into openings in the other splice bar, the tongues of one base plate being alternately arranged relatively to the tongues of the other base plate, depending curved arms carried by said base plates intermediate the ends of said splice bars and contacting beneath said base plates, 105 110 115

tapering keys extending through said splice bars and the tongues of said base plates, and cotter pins retaining said keys in position.

- 5 2. In a rail fastener, the combination with rails, of splice bars bracing said rails, base plates carried by said splice bars and supporting said rails, tongues carried by one of said base plates and extending into one of
10 said splice bars, tongues carried by the other base plate and extending into the other splice bar, enlargements carried by said splice bars intermediate the ends thereof, depending curved contacting arms carried

by said splice bars intermediate the ends 15 thereof, keys passing through said enlargements and some of said tongues and said arms, spikes passing through said splice bars and the other of said tongues, and means for retaining said keys in position.

In testimony whereof we affix our signatures in the presence of two witnesses.

JOHN A. PLUEBELL.
JOHN E. KAUTZ.
